UNITED STATES PATENT OFFICE.

CHARLES W. BECK, OF ROCKVILLE CENTER, NEW YORK, ASSIGNOR, BY MESNE ASSIGNMENTS, TO OXWELD ACETYLENE COMPANY, A CORPORATION OF WEST VIRGINIA.

ACETYLENE-GENERATOR.

1,033,864.

Specification of Letters Patent. Patented July 30, 1912.

Original application filed October 23, 1901, Serial No. 79,626. Divided and this application filed December 22, 1908. Serial No. 468,830.

To all whom it may concern:

Be it known that I, CHARLES W. BECK, a citizen of the United States, residing at Rockville Center, county of Nassau, State of New York, have invented certain new and useful Improvements in Acetylene-Generators, of which the following is a specification.

This invention relates to improvements in acetylene generators, and refers more specifically to an improved carbid feeding mechanism for feeding pulverulent or broken carbid.

The object of the invention is to provide an extremely simple mechanism, of the character referred to, containing a minimum number of movable parts and wherein the carbid is fed through a valve mechanism so constructed and arranged that the body of carbid is caused to bank up and seal the carbid discharge passage when the valve mechanism moves into closed position, the parts being so arranged with reference to each other as to provide great freedom of movement and to afford little liability of becoming clogged by the carbid.

A further object of the invention is to so construct and arrange the feed mechanism that it forms for itself a housing, preventing to a large extent access of vapor and dust to the mechanism.

The invention further includes certain improved details of construction and arrangement contributing to the conveniency and efficiency of the apparatus as a whole as will more fully appear from the detailed description.

The invention consists in the matter hereinafter described and more particularly pointed out in the appended claims and will be readily understood from the following description, reference being had to the accompanying drawings wherein:

Figure 1 is a view principally in side elevation, but with the feed mechanism and adjacent parts of the generator shown in vertical axial section of an apparatus embodying my invention; Fig. 2 an enlarged vertical sectional view of the feeding mechanism; Fig. 3 a detail view of a portion of the feed operating means; and Fig. 4 a side elevation of the rotary feed drum.

Referring to the drawings 1 designates as

a whole a lower reservoir or receptacle constituting the generating chamber, within which the carbid is plunged into a body of liquid. 2 an elevated carbid hopper and 3 a contracted intervening tubular support forming a chamber 4 within which the carbid feeding mechanism is located; the several elements mentioned being constructed, so far as their general features are concerned, in any well known or suitable manner.

The bottom wall 5 of the hopper is conical and terminates at its lower end in a short tubular chute 6 forming the discharge passage through which the carbid is fed from the hopper. This discharge chute is deflected to one side so as to discharge laterally. 70 A supporting casting 7 is connected to the chute and is formed with a horizontally extending shaft or stud portion 8, said stud portion projecting horizontally from the upper edge of the chute. Upon this stud is 75 journaled the feed drum 9, whereby said drum will be mounted eccentrically to the discharge opening of the chute. Secured to the chute and closing the inner end of the feed drum is a disk 10, the end of the chute 80 projecting through said disk and discharging into the drum. On the exterior of the drum near its outer edge is formed a beveled gear 11. The drum is provided in its outer vertical wall with a discharge aperture 12 85 through which carbid will drop into the generating chamber when said aperture is at the lowest point of its movement during the rotation of the drum.

In the construction illustrated herein the generator proper is arranged to communicate with a gasometer 13 forming an independent structure and the rising and falling of the bell 14 thereof is made the motive means for automatically actuating the carbid feeding mechanism of the generator. 90 To this end a drive shaft 15 is journaled to extend horizontally through the side wall of the contracted portion 3 of the generator at a point laterally opposite the feed drum, 100 that end of the drive shaft which projects within the generator being provided with a bevel gear 16 which is arranged to intermesh with the corresponding gear 11 formed integrally with and upon the periphery of 105 the feed drum, as indicated clearly in the

drawings. The opposite end of the drive shaft extends through a bracket support or bearing 18 mounted upon the lower gasometer member 13 and carries at its end a spur gear 19 arranged to intermesh with a rack-bar 20 mounted vertically upon a bracket 21 carried by the bell 14 of the gasometer.

As a convenient means of holding the gear 19 and rack 20 in mesh with each other and at the same time affording a suitable support for the bracket 18, a bar 21 is secured to the lower gasometer member and arranged to project vertically some distance above the latter, and upon the upper member or bell is mounted a guide 22 which embraces and slides upon the bar 21, as best shown in Fig. 3.

It will be obvious from the foregoing description that the rising and falling of the bell will impart a rotary movement to the drive shaft, first in one direction and then in the other, which motion of the shaft will impart an oscillatory movement to the feed drum, acting to carry the discharge aperture of the latter to its low point to permit carbid to drop therethrough into the generating chamber. The rack 20 is supported on the bell 14 in such a position and is so proportioned with respect to the gear 19 that when the bell rises the gear will be given one or more revolutions and the drum is so mounted that its aperture will be at its high point with respect to the discharge chute of the carbid hopper when the rack bar 20 is disengaged from the gear 19 by the continued upward movement of the bell. When the bell descends by reason of the reduction in gas pressure therein the rack bar will engage the gear 19 and rotate it in the reverse direction, thereby causing the feed drum to reverse its movement. These parts are so arranged and proportioned that the aperture in the feed drum will be at its high point when the bell is at the limit of either of its movements.

The gasometer is placed in communication with the gas space of the generator through a gas pipe 40 and the gasometer is likewise supplied with an outlet pipe 41 as usual. The generator is desirably provided with a filling pipe 42 for charging the generating chamber with liquid, the outer portion of said pipe 42 being arranged to extend vertically, provided with an overflow hole 43 which serves to indicate when the generator has been filled to the required height and also provided with a suitable cock 44. The generator is likewise provided with a discharge nozzle 45 controlled by a gate valve 46 through which the residue may be discharged and in order to facilitate the inspection and cleaning of the interior of the generator, a manhole is provided in its upper side closed by a suitable gas tight cover 47. The hopper is likewise

provided with a filling aperture closed by a screw plug 48.

The operation of the apparatus constructed and arranged as described has been sufficiently indicated in connection with the foregoing description to be entirely obvious and need not therefore be repeated at length. It is to be noted, however, that the construction of the carbid feeding mechanism is such that it is almost, if not quite, impossible for it to become choked or clogged by pieces of carbid small enough to pass through the feed opening, since there is no limit to the extent of rotary movement of the feed drum except that imposed by the limits of movement of the gasometer bell. It will be clear also that the feeding mechanism will serve to maintain itself sealed at all times, except when actually discharging, as long as a supply of carbid remains in the hopper.

It will be seen from the foregoing that I attain the several objects of the invention and produce with all a simple and economically constructed generator requiring but little skill in its manipulation, and therefore, well adapted for general use.

While I have herein described what I deem to be a preferred embodiment of the invention, yet it will be obvious that the details of construction may be modified to some extent without departing from the invention, and I do not, therefore, wish to be limited to these details, except to the extent that they are made the subject of specific claims.

The subject matter of the invention described herein forms a part of my original application, Serial No. 79,626, filed October 23d, 1901, of which original application this is a division.

Having thus described my invention, what I claim as new and desire to secure by Letters Patent, is:—

1. In a carbid feed mechanism the combination with a carbid receptacle provided with a discharge chute, of a drum mounted on a horizontal axis, the discharge chute delivering carbid into said drum below the axis thereof whereby the drum will be eccentric to the discharge chute, the drum being provided with a discharge opening in its outer vertical wall, said aperture being at one side of the axis of the drum, a gear formed on the exterior of said drum, a driving gear meshing with said drum gear, an expansible and collapsible gas holder, and means whereby the movement of said gas holder will rotate the gear.

2. In a carbid feed mechanism the combination with a carbid receptacle provided with a laterally extending discharge chute, of a drum mounted on a horizontal axis and eccentrically to the axis of the discharge chute, the said chute extending into said

drum near the lower wall thereof, the drum being provided with a discharge opening in its outer vertical wall, and means actuated by variations in gas pressure to rotate 5 the drum, whereby carbide will be intermittently discharged from said drum when the discharge opening thereof is at the low point in its revolution and the discharge chute will be sealed by carbide when the

discharge opening in the drum is at the 10 high point in the rotation of the drum.

In testimony whereof I hereunto affix my signature in the presence of two witnesses this 16th day of December, 1908.

CHARLES W. BECK.
